UNITED STATES PATENT OFFICE

123,458

DESIGN FOR A BUILDING

Mihran H. Kurkjian, Glen Rock, N. J.

Application October 20, 1939, Serial No. 87,779

Term of patent 3½ years

To all whom it may concern:

Be it known that I, Mihran H. Kurkjian, a citizen of the Republic of Armenia, residing in Glen Rock, county of Bergen and State of New Jersey, have invented a new, original, and ornamental Design for a Building, of which the following is a specification, reference being had to the accompanying drawing, forming part thereof, in which:

The rear of the building is substantially the same in appearance as the front thereof with the central door eliminated.

I claim:

The ornamental design for a building, as shown and described.

MIHRAN H. KURKJIAN.
